UNITED STATES PATENT OFFICE.

WILLIAM W. DEAN, OF ELYRIA, OHIO, ASSIGNOR TO THE DEAN ELECTRIC COMPANY, OF ELYRIA, OHIO, A CORPORATION OF OHIO.

TELEPHONE-TRANSMITTER.

No. 878,192.

Specification of Letters Patent.

Patented Feb. 4, 1908.

Application filed August 9, 1906. Serial No. 273,458.

To all whom it may concern:

Be it known that I, WILLIAM W. DEAN, a citizen of the United States, residing at Elyria, in the county of Lorain and State of Ohio, have invented certain new and useful Improvements in Telephone-Transmitters, of which the following is a specification, reference being had therein to the accompanying drawing.

10 My invention relates to telephone transmitters and has for its object the improvement of transmitters having inverted buttons, as described and claimed by me in my Patent No. 823,768, issued June 19, 1906. 15 In such transmitters as I have designed them I support the resistance button independently of the diaphragm and cause it to be pressed against the latter by suitable springs. The vibrations of the diaphragm are thus 20 communicated directly to the bottom of the resistance button or cup, and thence to the front electrode, said bottom itself in some cases constituting that electrode. Such a construction however, while it gives a highly 25 efficient instrument, does not enable the higher overtones to be picked up, and the general sensitiveness of the instrument to be increased, to quite the degree that I have found attainable by cutting out the central 30 portion of the main diaphragm, so that the bottom of the resistance cup may be itself exposed to the voice waves.

In order to stiffen the main diaphragm and at the same time prevent any undue projection on the face thereof, I form a flange around the orifice, which I cause to project rearwardly and insert the resistance cup in the opening with a shoulder resting on the flange.

40 By one feature of my present invention I am enabled to dispense with the accurate forming or boring of the flanged orifice in the diaphragm, heretofore necessitated by the fact that the resistance cup has been seated 45 therein, and at the same time I improve the structure of the cup, a second feature of my invention consists in the employment of a disk of cheap metal faced with a very thin sheet of platinum rolled on for the front 50 electrode. I have found it very difficult and quite expensive to properly plate the interior of the resistance cup or button, and gold is not the best possible material for an electrode. Platinum has always been con-

sidered the ideal material on account of its 55 power to resist corrosion and high temperature, but has been little used on account of its excessive cost. To obviate these difficulties I roll platinum of any desired thickness upon a base metal such as brass, German 60 silver, etc., and punch a disk out of such metal which I place within the forward end of the cup and spin the periphery of the cup around the disk.

My invention is illustrated in the accompanying drawing in which

Figure 1 is a transverse section of a transmitter embodying my improvements, and Fig. 2 is an enlarged detail of the front electrode.

70 Referring to the drawing 1, 2 and 3 represent the front plate, the inclosing shell, and the rubber mouth piece, respectively, all of the usual form. Resting upon the front plate and separated therefrom by the insulating gasket 4 is the main diaphragm 5 having a punched central opening 6 surrounded by the circular flange 7 adapted to engage and transmit motion to the carbon button.

75 Secured to the front plate in the usual manner is the bridge 8 which has connected to but insulated from it the plate 9 supporting the button stud 10. This stud carries the rear electrode 11, and interposed between the electrode and the flange 12 on the stud is a 80 supplemental diaphragm 13 of mica or the like. This supplemental diaphragm rests upon the edge of the cup 14 and is clamped in that position by a ring 15 which holds the diaphragm in its proper working position and 85 also strengthens the cup itself. A disk 90 formed of base metal 16, such as brass, German silver, or other like material, having rolled upon its inner surface a plating of platinum 17 of any suitable thickness, forms the 95 front electrode surface. This plate rests against a small annular shoulder 18 formed upon the inside of the cup and is held against said shoulder by the edge 19 of the cup, this being turned over preferably by spinning to 100 form a flange which surrounds the flange 7 of the diaphragm 5 and holds it in position. A suitable insulating lining is placed within the cup as usual to prevent short circuiting from the rear electrode to the cup. When the 105 parts are in place and before the stud 10 has been clamped within the bridge bearing plate by its set screw, not shown, a spring 20 is

made to bear against the upper face of the clamping ring 15 so as to hold the button in proper position upon the diaphragm.

- When assembling and adjusting the device 5 the diaphragm is first placed upon the front plate with the circular flange projecting inwardly and the button with its stud 10 placed within the bridge 8 and the bridge screwed into position upon the front plate. 10 The spring 20 now exerts pressure against the button and thereby forces the button into engagement with the diaphragm so that between the resilience of the main diaphragm and that of the spring 20 the button adjusts 15 itself. The set screw mentioned and not shown is then tightened upon the stud 10 and the transmitter when wired up is ready for use. The diaphragm in this instance has its circular flange seated against the plate 16 20 within the turned up portion 19 so that when assembling the parts the diaphragm is centered and held in position by the edges or flange formed by spinning the bottom into the cup. 25 Having thus described my invention what I desire to claim and secure by Letters Patent is:—
1. In a telephone transmitter, a cup containing granular material, a diaphragm having a stiffening rib or flange, and an electrode carried by said cup and intraperipherally engaged by said flange, said electrode receiving motion transmitted directly from the diaphragm through said flange. 30
  2. A telephone transmitter comprising a cup containing granular material, a diaphragm having a stiffening rib or flange, and an electrode carried by said cup, resting intraperipherally and directly against the edges 35 of said flange so as to receive motion therefrom. 40
  3. A transmitter comprising a cup containing granular material, a diaphragm having a central stiffening rib or flange and an electrode carried by said cup resting upon the flange and receiving motion intraperipherally therethrough from said diaphragm. 45
  4. A telephone transmitter comprising a resistance button, an electrode carried by 50 said button, securing means for said electrode, said securing means forming a flange, and a diaphragm having a stiffening rib or flange directly engaging said electrode inside of said securing means. 55
  5. A telephone transmitter having a resistance button comprising a metal cup, an

electrode movably connected therewith, another electrode held therein by upsetting the edges of the cup, said upset edges forming a flange, and means in engagement with 60 said last named electrode inside the flange for transmitting motion to the button.

6. A telephone transmitter having a resistance button comprising a containing cup, a platinum faced electrode held within the 65 cup by a flange formed on the cup, a carbon electrode extending into the cup and opposing said platinum electrode, an auxiliary diaphragm supporting the carbon electrode and clamped to the cup, granular carbon in 70 the cup between the two electrodes, and a main diaphragm having a flange engaging the platinum faced electrode inside the cup flange to give motion thereto.

7. In a telephone transmitter the combination with the main diaphragm having a stiffening rib or flange, of a resistance button comprising a cup, a platinum faced electrode forming the bottom of the cup, a carbon electrode extending piston fashion into the cup 80 and opposing said platinum faced electrode, granular carbon in the cup between the two electrodes, said cup being supported with its bottom resting upon and receiving motion from said flange. 85

8. In a telephone transmitter the combination with a main diaphragm having a stiffening rib or flange of a resistance button comprising a metal cup, a platinum faced electrode seated and held within one end of said cup 90 by spinning the metal thereof around the edges of the electrode, a carbon electrode extending piston-like into the cup, an auxiliary diaphragm carrying said carbon electrode and granular carbon in the cup between said 95 electrodes, the cup being independently supported with its bottom engaging directly against the rib or flange on the diaphragm.

9. In a telephone transmitter, a cup containing granular material, a diaphragm having a central perforation surrounded by a 100 stiffening rib or flange, and an electrode carried by said cup and intraperipherally engaged by said flange, said electrode receiving motion transmitted directly from the diaphragm through said flange.

In testimony whereof I affix my signature in presence of two witnesses.

WILLIAM W. DEAN.
